Attorney.

UNITED STATES PATENT OFFICE

JACOB MILHANDER, OF LOS ANGELES, CALIFORNIA

CUSHIONING DEVICE FOR DOORS AND WINDOWS

Application filed December 24, 1928. Serial No. 328,189.

This invention relates more specifically to a device for cushioning and sealing against movement, doors, casement windows and like structures.

5 The chief object of this invention is to provide a simple resilient cushioning device that may be readily installed on a door jamb to effectually prevent any rattling or movement of the door when the same is swung to a closed 10 position.

Another object is to provide a device that is of simple construction, economical of manufacture, and which may be readily attached to a door jamb or window frame without the 15 use of attaching means other than those possessed by such structures.

In the manufacture of auto-vehicles the doors are usually fitted very closely in their 20 openings, and in order to prevent undue rattling or movement of the doors rubber cushioning devices are employed on the latch side of the door jambs. These devices are quite effective when the vehicles are comparatively new, but when the doors and adjacent portions 25 of the vehicle bodies shrink by reason of atmospheric conditions and from other causes, it becomes necessary to replace the cushioning devices, which also shrink and dry out, with fresh ones to compensate for 30 such shrinkages.

By means of my simple air cushioning device the natural shrinkage of the doors are provided for and the same will always be held tightly in their frames against any 35 movement that would cause the same to rattle or creak.

In the drawings wherein a single embodiment of the invention is disclosed by way of example:

40 Fig. 1 is a perspective view of an auto-vehicle of the sedan type equipped with the cushioning device.

Fig. 2 is a face view of the device shown 45 in position on a vehicle door jamb.

Fig. 3 is a central vertical section of the device taken on line 3—3 of Fig. 2.

Referring more specifically to the drawings the device preferably consists of a molded rubber member 5, consisting of a flat base 6 about one-fourth inch thick and approxi-

mately one and one-half by two inches, the upper end of said plate being extended above the upper edge of the plate to form an attaching tab 7, provided with an opening 8 for the passage therethrough of a screw. 55 Molded on the outer face of the base 6 is a projecting portion 9 having a flat face 10 and bevelled side walls 11. By means of this projecting portion 9 a cavity 12 will be formed on the rear face of the base 6 for compressing 60 the air therein when the edge of the door 13 is brought thereagainst.

In practice the device may be readily and conveniently attached to the vehicle door jamb 14 and on a leaf 15 of one of the hinges 65 by removing one of the hinge screws 16 and passing it through the opening in the attaching tab. Although I have shown only a single device attached to the jamb which will in a majority of cases prove sufficient to prevent rattles in the doors, another may be secured in the same manner to the upper hinge 70 17.

When the device is in place on the door jamb and edge 18 of the door is brought thereagainst as when closing the same, the air in the cavity 12 will be compressed, and as the device is attached at only a single point movement of the base will be afforded, the 75 trapped or compressed air holding the door against any movement and thus eliminating 80 any rattles, squeaks, or other untoward noises.

It will be obvious that the device may be readily employed in connection with casement windows to effect a tight seal against the elements, and also the doors of building structures, not only to seal the same but to prevent noises occasioned by the quick shutting or slamming of the same.

I claim:

1. In combination with the frame of a door having a door hinged therein, of a base member formed of a resilient material provided with a cavity therein, said member adapted to be secured to that portion of the door frame to which the door is hinged with the rim of the cavity engaging the face of said door frame, whereby to seal the door in its frame 85 against movement.

2. A device of the class described comprising a body of resilient material having an air cavity formed therein adapted to be secured at one of its ends to the side face of a door frame, the cavity of the body being oppositely disposed against the door frame for compressing the air therein, whereby to permit of a sliding movement of the body and to compress the air in its cavity when the door frame
6 is brought thereagainst.

10 In testimony whereof I affix my signature.
JACOB MILHANDER.
